STAPLING DEVICE

Morris Abrams, Brooklyn, N. Y.

Application June 21, 1939, Serial No. 280,323

5 Claims. (Cl. 1-3)

This invention relates to stapling devices. It is particularly directed to stapling devices for driving U-shaped wire staples, for fastening together sheet material such as paper or fabric, or for tacking sheets onto wood or the like material which may be penetrated by the prongs of the staple.

In prior stapling devices jamming of two staples in the ejecting chute often results when a user 10 does not force the plunger down completely, leaving a staple in said chute, and then again strikes the plunger. Such jamming occurs because the prior devices were so constructed as to allow a second staple to move into the ejecting chute even though the first, partially driven staple is still in the chute. It is therefore an object of 15 this invention to provide a device of the character described in which jamming is prevented, the construction being such that unless a staple is substantially completely driven out of the ejecting 20 chute, it will prevent the succeeding staple from moving into the chute, so that if the plunger is struck again it will merely restrike the original staple and complete the clinching operation.

25 A further object of this invention is to provide in a stapling device of the character described, a staple magazine comprising an outer guide member and an inner guide member attached thereto, and together forming a passage of inverted U-shaped transverse cross-section, for the staples, said outer guide member having continuous inwardly extending guide flanges at the top to guide the staples throughout the length of the magazine, and integral upstanding walls extending from the inner edges of said flanges, forming part of the plunger housing and carrying the anchor for the feed spring, said walls nevertheless being flush with the side walls of 30 said outer guide member substantially throughout their entire height, whereby the parallel side walls of the plunger housing will contact the outer surfaces of said upstanding walls, as well as the outer surfaces of the side walls of said outer guide member, thereby resulting in a compact, 35 rugged and neat construction.

Another object of this invention is to provide 40 in a magazine for a stapling device of the character described, a one piece inner guide member having a top wall and downwardly extending side flanges, the top wall having punched tongues depressed into contact with the bottom wall of the outer guide member and riveted thereto, said bottom wall having upwardly recessed portions 45 to receive the rivet heads, whereby no parts of

the rivets extend either above said top wall or below said bottom wall, so as not to obstruct either the passage of the staples in the magazine or movement of the paper or other sheet to be stapled, beneath the magazine, the forward ends 5 of said guide members constituting part of the ejection chute for the staples, and the height of said guide members determining the height of said chute which is hence only little more than the height of a staple, whereby if a substantial 10 part of a staple is still in the ejection chute it will prevent another staple from moving in the chute.

Yet another object of this invention is to provide in a stapling device of the character described, 15 a staple magazine having a passage of inverted U-shaped cross-section for the staples, and an ejection chute at the forward end of the magazine, the construction being such that the chute does not extend to any substantial distance below said passage, whereby to prevent jamming of the staples in said chute.

Still another object of this invention is to provide in a stapling device of the character described, 20 a spring retracted driver carrying a plunger blade, and comprising a shank having a longitudinal groove, the driver housing having a lip projecting into said groove serving to stop the upward retraction of said driver.

A still further object of this invention is to 25 provide a compact, sturdy and durable device of the character described, which shall be relatively inexpensive to manufacture, easy to assemble, smooth and positive in operation, and yet practical and efficient to a high degree in use.

Other objects of this invention will in part be 30 obvious and in part hereinafter pointed out.

The invention accordingly consists in the features of construction, combinations of elements, and arrangement of parts which will be exemplified in the construction hereinafter described, 35 and of which the scope of application will be indicated in the following claims.

In the accompanying drawing, in which is 40 shown one of the various possible illustrative embodiments of this invention:

Fig. 1 is a side elevational view of a stapling device embodying the invention, with parts broken away and in cross-section;

Fig. 2 is a cross-sectional view taken on line 50 2-2 of Fig. 1;

Fig. 3 is a top plan view of the anvil portion of the improved device;

Fig. 4 is a perspective view of the inner guide 55

member, with parts broken away and in cross-section; and

5 Fig. 5 is a perspective view of the outer guide member with parts broken away and in cross-section.

10 Referring now in detail to the drawing, 10 designates a stapling machine embodying the invention, for fastening together sheets with usual U-shaped staples 10a, having stapling portions 10b and prongs 10c. The same comprises a base 11 having a pair of upstanding spaced, apertured ears 12 at its rear end. At the forward end of the base 11 is an anvil 13 formed with a usual cammed groove 14 to guide the prongs 10c of a 15 staple 10a inwardly.

20 Mounted on the apertured ears 12 is a transverse pivot pin or bolt 17, and pivoted to the bolt is a member 18 extending forwardly and disposed above the base 11. Member 18 comprises a staple magazine 19, for the staples 10a. Said magazine comprises an outer guide member 20, and an inner guide member 21 together forming a longitudinal passage of inverted U-shaped cross-section through which the staples 10a pass.

25 The outer guide member 20 comprises a pair of parallel side walls 22 interconnected by a bottom wall 23. Adjacent the rear end thereof, the side walls 22 are formed with downwardly extending ears 24 formed with aligned openings 25 to receive the pivoted bolt 17. The forward end of the bottom wall 23 terminates, as at 26, short of the forward ends 48 of the side walls 22; and the forward portions of said side walls are extended downwardly, as at 27, to the level of the underside of the bottom wall 23. Said bottom wall is formed with a plurality of upwardly raised or recessed portions 30, each formed with a rivet opening 31, for the purpose hereinafter appearing.

30 Integrally formed with the upper ends of the side walls 22 are inwardly projection horizontal flanges 34 extending substantially throughout the length of the outer guide member 20.

35 Extending upwardly from, and integrally with the inner edges of the flanges 34, are a pair 40 of upstanding parallel, substantially, similar, symmetrical disposed walls 35. Said walls 35 are disposed rearwardly of the forward end of member 20. The main portions of the walls 35 are flushed with the side walls 22, the lower ends of 45 said walls extending inwardly to the inner edges of the flanges 34.

50 The walls 35 are formed with aligned pairs of openings 37, for the purpose hereinafter appearing. One of the walls 35 is formed with an enlarged circular opening 38, and the other wall is formed with a square opening 39, aligned therewith. The walls 35 have front, vertical, inwardly extending aligned flanges 40, for the purpose hereinafter appearing.

55 The inner guide member 21 is disposed within the outer guide member and has a top wall 41 and downwardly extending, parallel, side walls 42. The side walls 42 have vertical extensions 43 at their lower ends. Said inner guide member rests 60 on the bottom wall 23 of the outer guide member and the portions 43 are disposed forwardly of the bottom wall 23. The top wall 41 of inner guide member 21 is parallel to the bottom wall 23 of the outer guide member 20. Said top wall 65 41 is formed with a pair of punched, downwardly depressed tongues 44 contacting the raised portions 30 of the bottom wall 23. Said tongues 44 are formed with openings 45 to receive therethrough, rivets 46 which attach said tongues to 70 said bottom wall.

75 It will be noted that the lower heads of the rivets are received within the raised portions 30, so as not to project below the bottom wall 23. Furthermore, since the tongues 44 are depressed below the top wall 41, the upper heads of the rivets do not project above said top wall. The forward edge 47 of the inner guide member is in a plane rearward of the forward edge 48 of the side walls 22, by a distance substantially equal to the thickness of one of the staples. The forward ends 34a of the flanges 34, terminate short of the forward edges 48 of the side walls 22, by a distance equal substantially to the thickness of a staple, and are flush with the edge 47 of the inner guide member 20.

10 It will now be understood that between the inner and outer guide members, there is formed an elongated passage of inverted U-shaped cross-section, through which the staples 10a pass, as they are urged forwardly, in the manner herein- 15 after appearing.

20 Attached to the upstanding walls 35, is a housing member 50 forming together with member 19, a housing or chamber 57 for a driver 51, and also forming an ejection chute 52, as will be ex- 25 plained hereinafter.

25 The member 50 comprises a pair of parallel, vertical side walls 53, interconnected by a front, vertical wall 54. The side walls 53 of member 50 contact the outer surfaces of the side walls 30 35 of member 20, and are riveted thereto by rivets 55 passing through the opening 37. Said walls 53 also contact side walls 22 of the outer guide member. The wall 54 is spaced forwardly of the flanges 40 and contacts the forward edges 48 of 35 the outer guide member 20. The lower edges of said walls 53 and front wall 54 are flush with the underside of bottom wall 23.

40 It will now be understood that the ejection chute 52 is formed between the inner surface of the front wall 54, and the forward edge 47 of the inner guide member 21 and end edges 34a of flanges 34. As the staples 10 are urged forwardly, the forwardmost staple will be pushed into the ejection chute 52, in which position it 45 may be driven downwardly in a manner herein- after appearing.

45 The front wall 54 is formed with a central, longitudinal outwardly grooved portion 54a, for the purpose hereinafter appearing. The upper end 50 of wall 54 has an inwardly extending lip 56. It will also be seen that the driver chamber is formed between the wall 54 and the flanges 40.

50 Mounted in the openings 38, 39 is a transverse shaft 60, to which is connected the inner end of 55 a feed spring 61 wound on said shaft. The outer end of the spring is connected to the usual feed member 62, having a handle portion 63 and a portion 64 slidably received in the staple passage. The spring 61 serves to feed the staples 10a forwardly in the usual manner.

55 The driver 51 is slidably mounted in the chamber 57, between the flanges 40 and the front wall 54 of the housing member 50. Said driver comprises a plunger 70 formed with a socket 71 in its 60 undersurface and being formed with a head 72 at its upper end. Said plunger 70 is furthermore formed with a groove 73 in its front face adjacent its upper end. The lip 56 of the front wall 54 projects rearwardly into said groove 73 and 70 serves to limit upward movement of the driver. On the head 72 is a rubber cap 74. Interposed between the lower end of the driver and the forward end of the outer guide member 20, is a coil compression spring 75 serving to normally raise 75

the driver. Fixed to the forward face of the driver, as by rivet 16, is a plate 17 projecting downwardly below the plunger and adapted to enter the ejection chute 52, when the driver is struck to drive a staple against the anvil 14. The head of the rivet may project into groove 54a.

Interposed between the underside of the magazine 19 and the base 11, is a usual coil compression spring 80, to normally tilt the member 18 upwardly.

It will be noted that the height of the ejection chute 52 is substantially equal to the height of one of the staples, plus the thickness of the bottom wall 23. If the driver is struck downwardly with insufficient force to completely eject a staple, the staple in the ejection chute will prevent a succeeding staple from entering said chute, and hence, when the driver is struck again, the blade will merely drive the partially ejected 20 staple through to complete the clinching operation.

In prior stapling devices, the ejection chute extends to such a distance below the lower ends of the normal position of the staple, that one 25 staple can be driven downwardly to a position where it is wholly below the lower ends of the staples, allowing a succeeding staple to enter the ejection chute when the driver is lifted, so that upon again striking the driver, the two staples 30 in the ejection chute will become jammed. With the present construction, jamming is effectively eliminated since the staple has to be driven substantially wholly out of the machine before it clears the succeeding staple sufficiently to allow 35 said succeeding staple to enter the ejection chute.

Since the heads of the rivets 46 are disposed wholly above the bottom wall 23 and wholly below the top wall 41, there is no obstruction to sliding movement of the device onto papers to 40 be stapled, and there is no obstruction as to passage of staples in the staple passage.

It will be noted furthermore that the flanges 34 of the outer guide member 20 extend substantially throughout the length of said guide member, forming a continuous guide for the saddle portions of the staples. Nevertheless, the up-standing walls 35 are integrally formed with the member 20, making for rigid construction. Said walls 35 are flush with the side walls 22 of the outer guide member, and the side walls 53 contact the walls 35, as well as the side walls 22, forming a smooth, compact and rugged construction.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A stapling machine comprising a base, a member pivoted thereto comprising an outer guide member having a bottom wall, side walls, and inwardly extending flanges at the upper ends of the side walls, an inner guide member within said outer guide member, said inner guide member having a top wall disposed below the flanges of the outer guide member, and parallel, side walls spaced inwardly of the side walls of said

outer guide member, the top wall of said guide member having downwardly punched depressed tongues contacting the bottom wall of said outer guide member and fastened thereto, said outer guide member being formed with integral, upwardly projecting walls extending from the inner edges of said flanges, whereby said flanges are continuous substantially throughout the length of said outer guide member, and a housing member having parallel, side walls receiving said upwardly projecting walls and fastened thereto, said housing member having a front wall contacting the forward edges of the side walls of said outer guide member, said flanges terminating short of the forward edges of the side walls of said outer guide member, and the forward end of said inner guide member terminating short of the forward edges of the side walls of said outer guide member, the lower edges of the side walls and front wall of said housing member being substantially flush with the underside of the bottom wall of said outer guide member.

2. In a stapling machine, a staple magazine comprising an outer guide member having a bottom wall, parallel side walls extending upwardly from said bottom wall, and inwardly projecting aligned flanges extending from the upper ends of said side walls, and an inner guide member within said outer guide member, said inner guide member having a top wall spaced below said flanges, and a pair of parallel side walls spaced inwardly from the side walls of said outer guide member, said flanges terminating short of the forward edges of the side walls of said outer guide member, and the forward end of said inner guide member terminating short of the forward edges of the side walls of said outer guide member, said top wall having downwardly disposed tongues, and rivets connecting said tongues to the bottom wall of said outer guide member.

3. In a stapling machine, a staple magazine comprising an outer guide member having a bottom wall, parallel side walls extending upwardly from said bottom wall, and inwardly projecting aligned flanges extending from the upper ends of said side walls, and an inner guide member within said outer guide member, said inner guide member having a top wall spaced below said flanges, and a pair of parallel side walls spaced inwardly from the side walls of said outer guide member, said flanges terminating short of the forward edges of the side walls of said outer guide member, and the forward end of said inner guide member terminating short of the forward edges of the side walls of said outer guide member, said top wall having downwardly disposed tongues, and rivets connecting said tongues to the bottom wall of said outer guide member, said bottom wall having upwardly recessed portions to receive the lower heads of said rivets, whereby said rivets do not project below said bottom wall.

4. A stapling machine comprising an outer guide member having a bottom wall and side walls, and inwardly extending, aligned flanges at the upper ends of said side walls, an inner guide member within the outer guide member and having a top wall disposed below said flanges, and downwardly extending side walls spaced inwardly from the side walls of said outer guide member, said outer guide member being formed with a pair of upwardly projecting walls extending from the inner edges of said flanges, a housing member having a pair of parallel, side

walls receiving and attached to said upstanding walls, said housing member having a front wall spaced from said upstanding walls and contacting the forward end of said outer guide member, 5 said flanges terminating short of the forward edges of the side walls of said outer guide member, and the forward edge of said inner guide member terminating short of the forward edges of the side walls of said outer guide member, a 10 plunger slidably mounted within the chamber formed between the front wall of said housing member and said upstanding walls, and a blade on said plunger adapted to press a staple into the ejection chute formed between said front 15 wall and the forward edges of said flanges and inner guide member.

5. A stapling machine comprising an outer guide member having a bottom wall and side walls, and inwardly extending aligned flanges at 20 the upper ends of said side walls, an inner guide member with the outer guide member, and having a top wall disposed below said flanges, and downwardly extending side walls spaced inwardly from the side walls of said outer guide mem-

ber, said outer guide member being formed with a pair of upwardly projecting walls extending from the inner edges of said flanges, a housing member having a pair of parallel, side walls receiving and attached to said upstanding walls, 5 said housing member having a front wall spaced from said upstanding walls and contacting the forward end of said outer guide member, said flanges terminating short of the forward edges of the side walls of said outer guide member, and the forward edge of said inner guide member terminating short of the forward edges of the side walls of said outer guide member, a plunger slidably mounted within the chamber formed between the front wall of said housing member and 10 said upstanding walls, and a blade on said plunger adapted to press a staple into the ejection chute formed between said front wall and the forward edges of said flanges and inner guide member, said plunger being formed with a groove 20 on its front face, and said front wall having a rearwardly extending lip at its upper end projecting into said groove.

MORRIS ABRAMS.
